UNITED STATES PATENT OFFICE.

CHARLES WEIS, OF LANCASTER, PENNSYLVANIA.

COLLAR.

1,273,702.

Specification of Letters Patent. Patented July 23, 1918.

Application filed May 25, 1918. Serial No. 236,591.

To all whom it may concern:

Be it known that I, CHARLES WEIS, a citizen of United States, residing at 534 Park avenue, Lancaster, in the county of 5 Lancaster and State of Pennsylvania, have invented new and useful Improvements in Collars, of which the following is a specification.

The invention relates to clothing and 10 more particularly to collars, and has for an object to provide a collar adaptable to military uniforms, and clothing of like character, especially military uniforms such as are worn at the present time, and on which 15 the collar can be conveniently and quickly adjusted, presenting a neat and effective appearance, in conjunction with the collar of the usual military jacket.

The invention comprehends among other 20 features a collar device by the use of which the device can be arranged beneath the usual upstanding collar of a military jacket, without the necessity of an undergarment to which the collar is to be attached, and further, 25 the invention comprehends a collar device in which the white collar portion does not necessarily have to be as large as the usual white collar now generally worn, thus reducing laundry expenses, the collar device 30 furthermore, being quickly applied and as easily removed.

Still further, instead of using a linen collar, I may employ a form of celluloid collar, and the body of my invention may be 35 made of the same color material as the collar of a military jacket, so as to make the entire structure present a neat and effective appearance.

Still further, my invention comprehends 40 various improvements in collar devices such as are set forth in an application for patent on a collar filed April 20, 1918, Serial No. 229,778.

In the further disclosure of the invention, reference is to be had to the accompanying drawing, constituting a part of this specification, in which similar characters of reference denote corresponding parts in all the views, and in which—

50 Figure 1 is a perspective view of the device showing the same applied, with parts broken away to disclose the underlying structure.

Fig. 2 is a fragmentary elevation looking 55 at the inside of the device.

Fig. 3 is a vertical sectional view through a portion of the device, and

Fig. 4 is a similar view of a slightly modified form.

Referring more particularly to the views 60 I disclose a military jacket 10 having the usual up-turned jacket collar 11, which it will be noted only extends up a short distance, the free ends of this jacket collar meeting at the front where the jacket is 65 closed. My device is employed to lie beneath the jacket and the jacket collar 11, and consists, substantially, of a fabric collar support 12, which may be of the same color material as the military jacket, said support 70 having its medial portion at the front where the ends of the jacket collar meet, with the ends of the collar support, indicated by the numeral 13, adapted to come together at the rear and be held by suitable clasps 14. 75 The main part of the collar support is formed of a stiffening 15, which is inclosed in or covered by a covering 15^a of the same color as the jacket collar of the military jacket. To secure the support in position beneath the jacket collar, the support at its 80 medial portion is provided with a depending flap 16, which comes beneath the jacket at the front.

A series of upstanding supporting members 85 17 are provided on the collar support to form a part thereof, and each consists of a stiffener 18 which can be secured to the stiffening 15 and project upwardly to have their free ends adjacent the upper part of 90 the collar support and extend slightly above the same, said stiffeners being covered with a suitable covering 19, the same color as the collar support. These supporting members are arranged in spaced distances and at the 95 point of connection of the collar support at the rear, one of said supporting members is provided, being located at the ends of the collar support, and immediately adjacent the point of arrangement of the clasps 14. The 100 collar element is indicated by the numeral 20 and consists, in fact, of a miniature turn-down collar as shown, said collar element being adapted to be arranged so that the free upstanding portions of the supports 105 will extend between the sides 21, 21^a of the collar element, and thus when the collar support with the collar element thereon is arranged in position to encircle the neck, with the jacket collar of the military jacket 110

encircling the collar support, it will be seen that the collar element will project just a sufficient distance to present a neat and desired appearance necessary to the proper 5 dress of a military uniform. The flap 16 of course extends beneath the jacket collar, holding the collar support in place, the jacket collar being also adapted to aid in performing this function.

10 In the modified form as shown, I have the upper ends of the supports, indicated by the numeral 25, beaded to conform to a beaded effect or portion 26 on the collar element, this being provided simply to conform to a 15 particular design of a slightly fancier appearance than the ordinary form of collar.

I claim:

1. In a collar device the combination with a collar support and a collar element, means 20 for connecting the free ends of the collar support, a series of spaced upstanding supporting members on the collar members on

the collar support and forming a part thereof, said supporting members projecting upwardly a slight distance beyond the upper 25 edge of the collar support, and adapted to have their free ends lie between the sides of the collar element when the collar element is applied to the support.

2. In a collar device the combination with 30 a collar support and a collar element, of a flap depending from the front of the collar support, means for connecting the free ends of the collar support at the rear, and a series of supporting members attached to the collar support and having their upstanding portions projecting up to and slightly beyond the upper edge of the support, with said upstanding portions adapted to fit between the sides of the collar element, said 35 40 collar element lying wholly inside of said collar support.

In testimony whereof I affix my signature.
CHARLES WEIS.
